UNITED STATES PATENT OFFICE.

MAY L. MUDD, OF WASHINGTON, DISTRICT OF COLUMBIA.

BED-PAN.

1,188,553.

Specification of Letters Patent. Patented June 27, 1916.

Application filed October 4, 1915. Serial No. 53,960.

To all whom it may concern:

Be it known that I, MAY L. MUDD, a citizen of the United States, and resident of the city of Washington, District of Columbia, have invented a new and useful Improvement 5 in Bed-Pans, which invention is fully set forth in the following specification.

The object of the invention is to provide a bed pan which can be used by either a male 10 or a female patient lying flat, that is, lying in normal position on his or her back without being raised.

With bed pans as heretofore constructed it has been necessary for the patient to be 15 raised in order that the pan might be inserted under him or her. This raising of the patient is very frequently injurious and it involves severe effort on the part of the nurse, especially when the patient is heavy 20 or is unable to assist.

By my invention I have provided a pan which can be readily used by either a male or a female patient for either urination or 25 intestinal evacuations without the movement of the patient from his or her normal position lying flat.

In the accompanying drawing I have illustrated one embodiment of the invention, this being the embodiment that I prefer, but it 30 will be understood that the invention can be embodied in other ways, within the scope of the appended claims, without departing from the spirit thereof.

Of the drawings; Figure 1 is a perspective 35 view; Fig. 2 is a side view with a part broken away; and, Fig. 3 is a plan view.

In describing the bed pan I will refer to the end which lies adjacent the patient's buttocks as the rear end, and to the opposite 40 end as the front end.

In the drawings, 1 represents the bottom of the pan which is flat to closely engage the surface of the bed. The rear wall 2 connects directly with the flat bottom 1 and its outer 45 surface extends continuously forward and upward from the bottom to the top forming an acute angle with the under surface of the bottom. The lines of the said outer surface of the rear wall which lie in longitudinal 50 vertical planes are preferably very slightly concaved as clearly indicated in Fig. 2. The said rear wall 2 is low, its top being below the anus of the patient when the pan is in use with a patient lying flat without 55 being raised. It will be understood that when I refer to a patient lying flat, I mean

lying with his back and buttocks resting on the bed, it being immaterial as concerns the use of the bed pan just what the position of the patient's head and shoulders may be. 60 The outer surface of said rear wall 2 of the pan is provided with two similar depressions 3-3 which are so shaped and spaced as to be adapted to receive the buttocks of the patient when the pan is pressed against him. 65 Between the said depressions 3-3 there is formed a projection 4 which is adapted to fit between the buttocks of the patient and closely engage his body between the base of the spinal-column and the anus. Preferably, 70 the depressions and the projection extend to the bottom of the pan, the rear edge of the bottom of which is shaped to conform to them. Preferably, the top edge or surface of the rear wall is slightly inclined downward and inward to insure the flow into the 75 pan of any liquids that may reach the said top surface. Without such inward inclination, pockets might be formed between the patient's body and the top surface of the 80 wall, which pockets would temporarily hold liquid and discharge it to the bed when the pan was removed. The inner surface of the rear wall 2 can be formed in any desired way, it preferably being inclined similarly 85 to the outer surface and extending in a smooth curve from one side of the pan to the other.

The pan is provided with side walls 5-5 which join the ends of the rear wall 2. The 90 walls 5-5 are provided at their tops with inward extending parts 6-6 which also join the ends of the rear wall and form shoulders 7-7. These shoulders are rounded at the corners and have upper surfaces 95 which are nearly plane and which are preferably slightly inclined toward the front. Preferably, the walls 5-5 gradually increase in height toward the front, the inward projections 6-6 providing two upward inclined surfaces. 100

The front wall of the pan is indicated at 8 and this is preferably substantially vertical. The side walls 5-5, together with their inward projecting members 6-6 join 105 this front wall, and the parts 6-6, being separated from each other, leave an opening at 9 through which the contents of the pan can be easily discharged. It will be understood that while I prefer to construct a pan 110 with the front portion thereof formed in the way just described, this part of the pan can

be otherwise constructed in accordance with the requirements.

When the bed pan is to be used the patient is allowed to remain in normal position lying flat, but the legs are slightly raised. The pan is placed under the legs and pushed backward into contact with the body, but without moving his buttocks. The depressions 3-3 receive the buttocks and the projection 4 passes between the buttocks into engagement with the body. The shape of the rear wall including the depressions and the projection is such that throughout its entire length it can engage the body, and its height is such that, when so engaged, it will lie below and to the rear of the anus, leaving the latter exposed to permit intestinal evacuations. It will be observed that the rear wall by virtue of its close contact with the body, will, in the case of a liquid discharge, prevent the flow of the said liquid along the surface of the body to the bed. As stated, the parts 6-6 of the said walls are inclined forward and upward, and preferably, though not necessarily, the patient's legs rest upon the aforesaid shoulder 7-7 and upon these inclined wall parts 6-6. When the patient's legs rest on the shoulders 7-7, and the wall parts 6-6, they form with the pan a liquid tight chamber, and there is no possibility for the escape of liquid downward along any part of the body. After use the bed pan can be easily removed and it can be easily emptied through opening at 9. The interior of the pan is smooth, and is free from minor crevices and depressions which would make cleaning difficult.

I am aware that bed pans of several forms have been heretofore proposed and used, but, so far as I am informed, none of these earlier pan's could be used for discharges from the bowels by any patient or successfully used by a female patient for urination without first raising the patient's buttocks from the bed. As already stated, a pan embodying my invention can be used without raising the patient or otherwise moving him or her from normal position.

A bed pan embodying my invention is well adapted for use in the giving of enemata and douches without raising the patient and is believed to be the first pan that can be so used.

What is claimed is:—

1. A bed pan provided with a low rear wall of such height that the top thereof fits below the anus of the patient while lying flat, the rear upper edge of said wall being shaped to closely engage the buttocks of the patient adjacent the anus on either side, whereby the pan may be placed in operative position without raising the patient.

2. A bed pan for use without raising the patient and while the patient is lying flat,

the said pan being provided with a low rear wall the top of which is below the anus of the patient when the pan is in use and the outer surface of which is inclined inward and upward from the bottom to the top thereof.

3. A bed pan for use without raising the patient and while the patient is lying flat, the said pan being provided with a low rear wall the top of which is below the anus of the patient when the pan is in use and the outer surface of which is inclined inward and upward from the bottom to the top thereof and formed with two depressions for receiving the buttocks of the patient and with a projection between the depressions for fitting between the buttocks of the patient.

4. A bed pan for use without raising the patient and while the patient is lying flat, the said pan being provided with a low rear wall the top of which is below the anus of the patient when the pan is in use and the outer surface of which is inclined inward and upward from the bottom to the top thereof and formed with two depressions for receiving the buttocks of the patient and with a projection between the depressions for fitting between the buttocks of the patient, the pan being also provided with side walls joining the said low rear wall with their tops sloping continuously upward therefrom.

5. A bed pan for use without raising the patient and while the patient is lying flat the said pan being provided with a low rear wall the top of which is below the anus of the patient when the pan is in use, and the outer surface of which is inclined inward and upward from the bottom to the top thereof and formed with two depressions for receiving the buttocks of the patient and with a projection between the depressions for fitting between the buttocks of the patient, the pan being also provided with side walls joining the low rear wall and forming with inwardly projecting, upwardly inclined upper parts forming rounded corner shoulders with the ends of said rear wall and so shaped as to be adapted to support the legs of the patient.

6. A bed pan for use without raising the patient and while the patient is lying flat, the said pan being provided with a low rear wall the top of which is below the anus of the patient when the pan is in use and the outer surface of which is inclined inward and upward from the bottom to the top thereof and formed with two depressions for receiving the buttocks of the patient and with a projection between the depressions for fitting between the buttocks of the patient, the pan being also provided with side walls joining at their ends with said low rear wall and formed with inward

projecting upper parts which in conjunction with the ends of the rear wall form rounded corner shoulders with approximately flat upper surfaces.

5 7. A bed pan for use without raising the patient and while the patient is lying flat, the said pan being provided with a low rear wall the top of which is below the anus of the patient when the pan is in use and the outer surface of which is inclined inward and upward from the bottom to the top thereof and formed with two depressions for receiving the buttocks of the patient

and with a projection between the depressions for fitting between the buttocks of the patient, the pan being also provided with a substantially vertical front wall and with side walls joining the rear and front walls and formed with inward projecting upper parts separated from each other throughout thus leaving an opening adjacent the front wall to facilitate emptying.

In testimony whereof I have signed this specification.

MAY L. MUDD.
